UNITED STATES PATENT OFFICE.

FRANK M. DIXON, OF JEFFERSON CITY, MISSOURI.

IMPROVEMENT IN STABLES.

Specification forming part of Letters Patent No. **179,901**, dated July 18, 1876; application filed April 4, 1876.

To all whom it may concern:

Be it known that I, FRANK M. DIXON, of Jefferson City, Cole county, Missouri, have invented a new and Improved Safety-Stable, of which the following is a specification:

My invention is a contrivance for hitching a horse and fastening a stable-door in such a manner that the horse will be freed and the stable-door opened in case of fire in the stable; also, a contrivance for sounding an alarm at the same time.

Figure 1 is a transverse section of a stable having my improved appliances, and Fig. 2 is a longitudinal sectional elevation of it.

Similar letters of reference indicate corresponding parts.

A is a cord, of cotton or other combustible material, stretched along the space above the stable, from side to side, to which the halter B of the horse is attached; also, a cord, C, holding the door E shut—say, by a chain, F, and a padlock, G—and the door has a spring, H, (dotted,) to throw it open when the cord is released. I is another cord, extending along the space above the stable, from

side to side, and connected to an alarm-bell, J, and also having the halter and the door-cord attached, so that when the cords A are burned off by fire the door will spring open, the horse will be released for escape, and the alarm-bell will sound. The halter will pass down from the space above, where it is attached, to cords A and I through guides K, and the door-cord will pass along through suitable guides L.

Having thus described my invention, I claim as new and desire to secure by Letters Patent—

1. The combination of the hitching-cord A and door-cord C, arranged as shown, with a spring-door, E, substantially as and for the purpose set forth.
2. The combination of the hitching-cord A, halter B, and door-cord C, with the door E and alarm-bell J, substantially as herein set forth, for the purpose specified.

FRANK M. DIXON.
